(57) **CLAIM**

The ornamental design for a ring, as shown and described.

DESCRIPTION

FIG. 1 is a top view of a ring showing my new design;

FIG. 2 is a side view thereof;

FIG. 3 is a front view thereof;

FIG. 4 is a top perspective view thereof; and,

FIG. 5 is a bottom view thereof.

The broken lines showing a portion of the shank and gemstones represent portions of the ring which form no part of the claimed design.

1 Claim, 5 Drawing Sheets

FIG. 1

FIG. 2

FIG. 3

FIG. 4

FIG. 5
